UNITED STATES PATENT OFFICE.

RALPH D. CHANDLER, OF SPICELAND, INDIANA.

ADJUSTABLE ELECTRIC LAMP.

1,171,171.

Specification of Letters Patent.

Patented Feb. 8, 1916.

Application filed September 21, 1914. Serial No. 862,804.

To all whom it may concern:

Be it known that I, RALPH D. CHANDLER, a citizen of the United States, residing at Spiceland, in the county of Henry, State of Indiana, have invented certain new and useful Improvements in Adjustable Electric Lamps; and I do hereby declare the following to be a full, clear, and exact description of the invention, such as will enable others skilled in the art to which it appertains to make and use the same.

This invention relates to electric lamps, and has for its object the provision of an electric lamp which may be adjusted to any desired position.

An important object is the provision of a device of this character which will be simple and inexpensive in manufacture, efficient and durable in use, neat in appearance and a general improvement of the art.

With these and other objects and advantages in view, the invention consists in the novel construction and arrangement of parts as will be hereinafter more fully described and claimed, and illustrated in the accompanying drawing, in which—

Figure 1 is a side elevation of my lamp constructed as a wall lamp, Fig. 2 is a perspective view, Fig. 3 is a sectional view on the line 3—3 of Fig. 1.

Referring more particularly to the drawing and especially to Figs. 1, 2 and 3, the numeral 5 designates a plate provided with suitable holes for the passage of screws 6 whereby the plate may be secured upon a wall or other desired place. Formed upon or secured upon the plate 5 are forwardly extending arms 7 between which is pivotally secured a member 8 by means of a bolt 9 secured in place by a suitable nut 10. The member 8 is thus horizontally revoluble between the arms 7. The front portion of the member 8 is provided with a recess 11 within which is pivoted as by means of a bolt 12 a forwardly extending arm 13 which is therefore capable of swinging vertically.

The bolt 12 is provided with a suitable nut 14. Secured upon the forward end of the arm 13 is a key socket 15 which passes through an opening in a concaved reflector 16 secured upon the forward end of the arm 13. An incandescent lamp 17 is threaded within the socket 15 in the usual manner. Wires 18 are connected with the socket 15 in the usual manner and extend along the arm 13, through the member 8 and preferably through a hole 19 in the plate 5 from which they lead to any suitable source of current.

It will be observed that when the lamp is in use, it may be adjusted to throw the light in any desired direction by virtue of the fact that the member 8 may be moved laterally and the arm 13 moved vertically.

It will be readily understood that I reserve the right to make various changes in the form, construction and arrangement of parts without departing from the spirit of the invention or limiting the scope of the subjoined claim.

Having thus described my invention, I claim:

An electric lamp comprising a supporting plate, a pair of forwardly extending arms thereon disposed one above the other, a member pivoted between said arms and adapted to be rotated, said member provided with a longitudinal slot and transverse openings communicating with said slot, a bolt arranged in the said transverse openings, a forwardly extending arm pivoted on said bolt within said slot and adapted to swing vertically, a reflector on the end of said arm, a socket carried by the end of said arm and extending through said reflector, and an incandescent lamp in said socket.

In testimony whereof, I affix my signature, in the presence of two witnesses.

RALPH D. CHANDLER.
